DESIGN FOR A DISPLAY CASE

Samuel H. Elliott, Cleveland, Ohio, assignor to The Standard Oil Company, Cleveland, Ohio, a corporation of Ohio

Application October 21, 1931, Serial No. 41,474

Term of patent 7 years

To all whom it may concern:

Be it known that I, SAMUEL H. ELLIOTT, a citizen of the United States, and a resident of Cleveland, county of Cuyahoga, and State of Ohio, have invented a new, original, and ornamental Design for a Display Case, of which the following is a specification, reference being had to the accompanying drawing forming a part thereof.

In said annexed drawing:—

The sole figure is a perspective view of a display case embodying my new design.

I claim:—

The ornamental design for a display case as shown.

Signed by me this 17th day of October, 1931.
SAMUEL H. ELLIOTT.
